UNITED STATES PATENT OFFICE.

ROBERT EDWIN REARDON, OF OTTAWA, ONTARIO, CANADA.

TARGET-PRACTICE ROD.

1,227,313.

Specification of Letters Patent.

Patented May 22, 1917.

Application filed February 24, 1917. Serial No. 150,842.

To all whom it may concern:

Be it known that I, ROBERT EDWIN REARDON, a subject of the King of Great Britain, and resident of the city of Ottawa, in the 5 Province of Ontario and Dominion of Canada, have invented certain new and useful Improvements in Target-Practice Rods, of which the following is a full description.

This invention relates to an improved 10 target practice rod of the type comprising a tube adapted to be inserted in the barrel of a rifle or fire arms, and a spring retracted rod in the tube adapted to be propelled by the hammer of the fire arm and to be projected to strike a suitable target.

The objects of the invention are to simplify and improve the construction of the device to enable it to more effectually perform the functions required of it. 20 One of the difficulties experienced with target practice rods of the present type has been the turning of the striking rod in the sleeve, whereby it is rendered more difficult to correct any error in the alinement of the 25 rod. This difficulty is overcome in the present invention by providing guiding means, such as a groove in the tube forming a guiding rib on the interior to which is fitted a suitable guide member on the rod.

30 A further object of the invention is to provide an improved and simplified form of joint used when the rod is constructed in two parts.

When the target practice rod is used with 35 a dummy cartridge placed in the magazine of the rifle, it is necessary the striking arm should be of a shorter length to that used when the hammer strikes the rod directly, and the present invention provides a simple 40 and effective means for the length of the striking arm being varied.

The invention also includes an improvement to the dummy cartridge used for magazine fire and to the muzzle clip adapted to 45 hold the tube in position.

For a complete understanding of the invention reference is made to the following specification and accompanying drawings forming part thereof.

50 In the drawings,

Figure 1 is a plan view of the rod partially in section.

Fig. 2 shows a longitudinal sectional elevation.

55 Fig. 3 is a longitudinal sectional view

through the joint between the two sections of the rod.

Fig. 4 is a section on the line 2—2 of Fig. 1.

Fig. 5 is a section on the line 3—3 of Fig. 2.

Fig. 6 is a perspective view of one section of the jointed rod.

Fig. 7 is a sectional view of the dummy cartridge.

In the drawings like characters of reference indicate corresponding parts in all the figures.

Referring to the drawings, A represents a metal tube adapted to be inserted into the 70 barrel of a rifle, being provided at the outer end with a bushing 10 adapted to abut the muzzle of the rifle barrel, and being held in position thereagainst by means of a muzzle clip 11.

The muzzle clip comprises a hook shaped flange 12 adapted to embrace the upper side of the bushing 10, side flanges 13 and 14 adapted to bear against the face of the bushing 10, and a lower retaining flange 15 having a projection 16 bearing against the bushing 10 and having hook shaped end 17 adapted to engage the foresight band of the rifle and so retain the device in position.

The rod A is formed in two sections, 20 and 21, connected together by an improved form of joint forming part of the present invention. This joint comprises a socket 22 having a longitudinal rib 23 formed on the side and provided with a clearance space 90 24 at a point a given distance inwardly from the end of the socket.

The portion 21 of the rod is formed with a rod or plug 25 set into and suitably secured to the end of the rod, and adapted to fit the socket 22. On a reduced or grooved portion of the plug 25 is mounted a rotatable sleeve 26 formed with a longitudinal groove 27 adapted to fit the rib 23, adapted in one position to register with a corresponding groove 28 formed on the head 29 of the plug or rod 25. To retain the sleeve in this position in which the joint is locked or unlocked, a spring detent device is provided between this sleeve 26 and the rod 25. This 100 spring detent device comprises a spring tongue 30 conveniently cut directly out of the sleeve itself, which is formed of steel or like spring metal. The tongue 30 is formed with a stud 31 adapted to engage with one

105

110

of two diametrically opposite recesses 32 and 33 in the plug 25.

When the two parts are to be connected together, the groove 28 is brought into alignment with the groove 27 and the plug and sleeve inserted in the socket, when the head 29 comes opposite the clearance space 24 in the rib 23, the two parts 20 and 21 are turned relatively to each other, the rib 23 engaging the groove 27 will prevent the sleeve 26 turning, this will carry the grooves 27 and 28 out of registration with each other and thereby prevent separation between the two parts of the rod.

15 Within the portion 20 of the rod A the striking rod B is mounted and journaled at the fore end in suitable bushings 41 and having a plug 42 at the rear end fitting the inside of the tube. This rod is spring retracted by means of a compression spring 43 extending between the bushing 41 and the plug 42. The forward striking end 44 is formed in a suitable way to cause it to perforate or mark the target to which it strikes, 20 as for example, by forming a needle point thereon.

To prevent the striking rod B turning with respect to the tube A and thus making it difficult to correct any inaccuracy in alignment, a longitudinal rib 45 is formed on the interior of the tube, as for example, by pressing the groove in the tube, the plug 42 is adapted to form a guide block with a notch or recess 46 to receive the rib.

35 The rear section 21 of the tube has mounted therein, what may be termed "the hammer rod C" comprising a tubular section 50 which fits closely to the tube 21, and a rod section 51 secured to the tube section and extending through the plug 25 being formed at its outer ends with a striking head 52. This rod is also spring retracted by means of a spring 53 extending from the plug 25 to the tubular section 50.

40 To enable the length of the hammer rod to be changed, I provide a reversible end piece 55 adapted to fit the end of the section 50. This end piece is formed with a collar 56 near one end and with grooves 57 and 58 on opposite sides of the collar. These grooves are adapted, when either end of the collar is inserted in the tubular portion 50, to be engaged by a spring tongue 59 formed on the portion 50 adapted to take in either 45 one of the grooves 57 or 58. It will be seen that by reversing the end of the end piece 50, the length of the hammer rod may be greatly varied.

When the rod is used for magazine practice, it is necessary to have specially formed cartridges such as shown in Fig. 7.

These cartridges comprise an outer casing 60 shaped and the size of an ordinary cartridge, and a reciprocal plunger 61 mounted in the casing and spring retracted by means

of a spring 62 extending between the guard member 66 on the plunger and the collar 63 supported in the cartridge by the sleeve 63^a. The head 65 of the plunger extends through the end 64 of the cartridge and occupies the same position as the percussion cap of a live cartridge and is adapted to be struck by the hammer of the rifle and projected forwardly. To prevent the compression spring 62 being unduly compressed when the plunger is projected forwardly a guard member 66 is mounted on the plunger formed with arms 67 adapted to engage the collar 63 and arrest the movement of the plunger before the spring is entirely compressed. The forward end of the plunger is adapted to engage the end piece 55 of the hammer rod, the shorter end being used for magazine practice.

In the operation of the device the two parts of the tube are connected together and placed in a barrel of a rifle, the muzzle clip 11 engaging the fore sight band of the rifle. The hammer or bolt of the firing mechanism of the rifle, when operated, is adapted to strike the end piece 55, projecting the hammer rod C forwardly, which propels the striking rod B forwardly to impinge on the face of the target.

When the device is to be used for magazine practice, the end piece 55 is reversed and the mechanism of the rifle is filled with dummy cartridges constructed as shown in Fig. 7. When operated the hammer or bolt of the rifle will project the rod 61 of the target forwardly which will operate the hammer rods and striking rods in the manner already described.

As many changes could be made in the above description and many apparently widely different embodiments of my invention within the scope of the claims constructed without departing from the spirit or scope thereof, it is intended that all matter contained in the accompanying specification and drawings shall be interpreted as illustrative and not in a limited sense.

What I claim as my invention is:

1. A target practice rod comprising a tube adapted to extend longitudinally on the interior of the barrel of a fire arm and from end to end of the same, a reciprocable rod in the tube of relatively much smaller diameter than the tube, a guiding bushing in the tube forming a bearing for the rod, and means on the interior of the tube adapted to prevent turning of the rod with respect to the tube, said means comprising a longitudinal groove extending from the end of the tube and forming a rib on the underside and a plug on the rod having a groove to fit the rib.

2. A target practice rod comprising a relatively thin metal tube having a longitudinal groove pressed therein forming a

rib on the interior, a reciprocable striking rod in the tube, and a guide member on the rod grooved to fit the rib.

3. In combination a socket having a longitudinal rib on the inside formed with a clearance space at one point, a rod adapted to fit the socket, a rotatable sleeve on the rod adapted to fit the socket, and having a groove to receive the rib on the socket and

10 a head on the rod adapted to fit the clearance space and being formed at one part with a groove adapted to register with the groove in the sleeve when being inserted, but adapted to be moved out of registration when it is desired to lock the rod and socket together.

4. In combination a socket having a longitudinal rib on the inside formed with a clearance space at one point, a rod adapted 20 to fit the socket, a rotatable sleeve on the rod adapted to fit the socket and having a groove to receive the rib on the socket and a head on the rod adapted to fit the clearance space and being formed at one part 25 with a groove adapted to register with the groove in the sleeve when being inserted, but adapted to be moved out of registration when it is desired to lock the rod and socket together, and a spring detent 30 device between the sleeve and the rod.

5. In combination a socket having a longitudinal rib on the inside formed with a clearance space at one point, a rod adapted to fit the socket, a rotatable sleeve on the 35 rod adapted to fit the socket and having a groove to receive the rib on the socket and a head on the rod adapted to fit the clearance space and being formed at one part 40 with a groove adapted to register with the groove in the sleeve when being inserted, but adapted to be moved out of registration when it is desired to lock the rod and socket together, and a spring detent device between the sleeve and the rod, said spring 45 detent device on the sleeve adapted to engage a corresponding recess formed in the rod.

6. In combination, a tube, a rod fitting the same, a rotatable sleeve on the rod, 50 means extending between the sleeve and the tube adapted to prevent relative rotation, but adapted to permit rotation of the rod relative to the tube when in a given position, said rod being only adapted to be withdrawn from the tube when in a given relative position.

7. In combination, a tube, a rod fitting the same, a rotatable sleeve on the rod, means extending between the sleeve and the tube adapted to prevent relative rotation, but adapted to permit rotation of the rod relative to the tube when in a given position, said rod being only adapted to be

withdrawn from the tube when in a given relative position, and a spring detent device 65 operating between the rod and sleeve.

8. In a target practice rod, a tube, a striking rod therein, and an adjustable end piece adapted to be placed and held in two different positions, the length of the entire 70 rod being shorter in one position than in the other.

9. In a target practice rod, a tube, a striking rod therein and a reversible end 75 on the striking rod adapted to change the length of the rod.

10. In a target practice rod, a tube, a striking rod therein having a socket at the inner end, a reversible end piece in the socket adapted to change the length of the 80 rod.

11. In a target practice rod, a tube, a striking rod therein having a socket at the inner end, a reversible end piece in the socket, said end piece being formed with a 85 collar and grooves on opposite sides of the collar and a spring tongue on the tube adapted to be set in said groove.

12. In a target practice rod, the combination with a tube and a reciprocable striking 90 rod therein, of a dummy cartridge having a spring retracted plunger therein, adapted to be projected by the hammer of the rifle, and means for arresting the outward movement of the plunger before the spring is 95 entirely compressed.

13. The combination with a target practice rod including a tube adapted to extend in the rifle barrel and a spring actuated rod therein, of a muzzle clip having a hook 100 shaped flange adapted to engage the end of the practice rod, a portion extending parallel with the barrel of the rifle and a hook on the end of the said portion adapted to engage the fore sight band on the 105 rifle.

14. The combination with a target practice rod including a tube adapted to extend in the rifle barrel, and a spring actuated rod, of a muzzle clip having means 110 to engage opposite sides of the end of the tube, and having other means adapted to engage the rifle barrel.

15. The combination with a firearm adapted to receive cartridges, of a tube adapted 115 to extend in the barrel of the firearm, a spring retracted rod in the tube, the inner end of the rod being adapted normally to lie in the path of the hammer or firing pin of the firearm, and means for shortening the 120 length of the rod to permit a dummy cartridge to be inserted between the firing pin and the end of the rod.

In witness whereof I have hereunto set my hand.

ROBERT EDWIN REARDON.
